DESIGN FOR SPOON HANDLES.

HENRY HEBBARD, OF NEW YORK, N. Y.

Design No. 2,531, dated December 18, 1866.

The Schedule referred to in these Letters Patent and making part of the same.

TO ALL WHOM IT MAY CONCERN:

Be it known that I, HENRY HEBBARD, of the city, county, and State of New York, have invented or produced a new and original Design for Ornamenting the Handles of Spoons, Forks, and other articles of table cutlery; and I do hereby declare that the following is a full description of the same, reference being had to the accompanying drawings forming a part of this specification; the same letters of reference, wherever they occur, referring to like parts.

Figure 1 is the front side of the fork.

Figure 2 is the back side of the fork.

Letter *a* represents the shield, which is shaped somewhat like a lance, the point ending in the upper end of the stem or handle *b*, which, at its lower end, joins on to the heel *c* of the blade *d*. Surmounting the head of the shield is a trefoil, *e*, having a raised flat marginal thread, *f*. The base of the trefoil is supported upon a flat scroll-thread, *g*, forming the outer and upper corners of the shield, and thence extending down the outer edges of the shield to a point at the junction of the shield with the stem. In the centre of the trefoil is a raised ivy leaf, *h*, and below it, and projecting down upon the shield, is a raised fawn's face, *i*, from the temples of which a raised flat thread, *j*, curves outwards about the eighth of an inch, and then, at a sharp angle, and at about an eighth of an inch from the outer marginal thread, bends down around the shield as an inner marginal thread to its junction with the stem, where they cross so as to form an open square, *k*, with the point of the outer marginal thread, and thence as a continuous thread they pass down the edges of the stem to the heel, where they join together in an upward projecting point on the centre of the stem. In the space between the inner and outer marginal threads around the shield, and in the hollow square at its point, are a number of raised figures, *l*, of a diaper pattern. Letter *m* is an ivy stem, with three leaves attached to it, extending down the middle of the handle from the point of the shield; and *n* is a single ivy leaf, with buds offshooting from it, extending up the middle of the handle from the upward projecting point of the marginal threads at the heel of the fork, below which point, and projecting down towards the blade, is a small pine-like figure, *p*, to complete the design on the front side of the fork or spoon. On the reverse or back side of the fork, *a*² represents the shield, and *b*² the trefoil surmounting it, and *c*² the raised ivy leaf in the centre of it, and *d*² the flat scroll, forming the support for the trefoil, and thence the outer marginal line or thread of the shield to a point at the junction of the shield with the stem, where they cross and form the head of an arrow, *e*², the point of which projects down the middle of the stem of the fork. On the inner side of the shield is another raised thread, *f*², at about an eighth of an inch from the outer thread, which passes around the shield, thence crossing at its lower point, so as to form an open square with the outer marginal thread also crossing at that point, and then down the edges of the handle or stem *g*² to the heel, where it branches into two parts, one part of which losing itself in the blade or heel of the fork, whilst the other branches, forming an interlaced figure, *h*², having their ends united in an arrow-head figure, *i*², projecting upwards of the handle between the marginal threads. Below the figure *h*² is a branch of ivy, *r*, with two side and one middle or pointed leaf, covering the heel of the fork, to complete the design for ornamenting the back side of the fork.

Having now described my invention of a new and original design for ornamenting the handles of spoons, forks, and other articles of table cutlery—

I claim the design for the handle of forks, spoons, and other articles of table ware, as shown and described.
